CLAIM

The ornamental design for a case for a tablet computer, substantially as shown and described.

DESCRIPTION

FIG. 1 is an isometric view of the front of a case for a tablet computer when folded showing our new design;

FIG. 2 is a side elevation view thereof;

FIG. 3 is a bottom elevation view thereof;

FIG. 4 is an interior plan view of the case when opened and laying flat;

FIG. 5 is an isometric view thereof;

FIG. 6 is an interior isometric view of the case when partially open;

FIG. 7 is an interior isometric view of the case in easel position;

FIG. 8 is a rear isometric view thereof;

FIG. 9 is a side elevation view thereof; and,

FIG. 10 is an interior isometric view of the case in easel position on its side.

1 Claim, 10 Drawing Sheets
